DESIGN FOR A TEXTILE FABRIC

Robert J. Murray, Philadelphia, Pa., assignor to Kaufman Plush Company, Philadelphia, Pa., a corporation of Pennsylvania

Application November 10, 1939, Serial No. 88,181

Term of patent 3½ years

To all whom it may concern:

Be it known that I, Robert J. Murray, a citizen of the United States, residing at Philadelphia, in the county of Philadelphia and State of Pennsylvania, have invented a new, original, and ornamental Design for a Textile Fabric, of which the following is a specification, reference being had to the accompanying drawing, forming part thereof.

The figure is a plan view of a textile fabric
showing my new design.

I claim:

The ornamental design for a textile fabric, as shown.

ROBERT J. MURRAY.
